CLAIM

The ornamental design for a pizza cutter, as shown and described.

DESCRIPTION

FIG. 1 is a front perspective view of a pizza cutter showing my new design;

FIG. 2 is a front elevation view thereof, with a rear elevation view thereof being a mirror image of the front elevation view;

FIG. 3 is a top plan view thereof;

FIG. 4 is a bottom plan view thereof; and,

FIG. 5 is a right side elevation view thereof, with a left side elevation view thereof being a mirror image of the right side elevation view.

The line shading on the handle surfaces, at the top edge surface and bottom edge surface of the pizza cutter depict a curved surface. The line shading on front and rear surfaces of the pizza cutter blade depict a flat surface. The broken lines shown in the drawings depict portions of the article that form no part of the claimed design.
